MEANS FOR RELEASING MUSIC COMB
VIBRATORS FROM THEIR PLUCKING
ELEMENTS

Theodore R. Duncan, North Hollywood, Calif.

Application January 6, 1950, Serial No. 137,048

10 Claims. (Cl. 84—95)

1

This invention has to do with music playing devices of the music box type wherein a rotatable element having projections is operatively associated with a music comb having vibrator teeth which extend into the path of the projections for selective actuation or plucking thereby as the rotatable element is turned.

Music box devices with which I am familiar, particularly those embodying a rotatable drum with radially extending plucking projections or fingers for actuating the vibrators of the music comb, and also those of the type employing a rotatable disk with plucking projections extending laterally therefrom, require relatively close tolerances in manufacture and assembly for the reason that the plucking projections must individually engage and release the vibrators within a limited arc or period of movement thereof to have a practicable device.

It is obvious that unless the plucking projections release the vibrators within a short period of travel, the plucking projections have to be spaced relatively far apart and in consequence only a few projections could be placed around the plucking element or drum in the path of each vibrator. Also, it is obvious that as the diameter of the plucking drum is increased, as in an attempt to gain a greater number of plucking projections around the drum, the arc of movement of the projections is on a greater radius with the result that the plucking projections do not release the vibrators until the projections have traveled a greater distance than the distance required for projections on a drum of smaller diameter.

Another disadvantage of music boxes is that, even when the parts are made to rigid specifications and carefully assembled, if the composition to be played requires the close or rapid repetition of the same note, it is necessary to provide two or more vibrators of the same pitch for that note, the vibrators being successively plucked by their own plucking fingers, for the reason that a single vibrator after having been plucked will vibrate into the oncoming plucking element unless that element is too far away to quickly pluck the vibrator.

It is therefore an object of this invention to provide a music box construction which eliminates the necessity of observing or carrying out close tolerances in the manufacture and assembly of music box devices of the type indicated.

Another object is to provide an inexpensive construction for music boxes of a character which can easily be manufactured and which produces good tonal quality.

2

A particular object of the invention is to provide a positive means for controlling the escape or release of the vibrator teeth of the music comb after actuation thereof by the relatively movable plucking projections. In this connection it is an object to provide means for disengaging or releasing the vibrator teeth of the comb from the plucking projections after they have been moved a predetermined distance by the plucking projections of the drum or other actuating element.

A further object of the invention is to provide, in a music box construction having relatively movable vibrator teeth and plucking elements therefor, means for camming or diverting the vibrator teeth out of the path of the plucking projections as the teeth are actuated by the projections to thereby positively release the teeth, leaving them free to vibrate.

Another object is to provide means for quickly releasing the vibrators from their plucking elements to enable a single vibrator to be successively plucked in rapid sequence.

These and other objects will be apparent from the drawings and the following description thereof.

Referring to the drawings:

Fig. 1 is a plan view of a music box device embodying the invention;

Fig. 2 is an enlarged view similar to Fig. 1 but showing a portion of the upper wall of the music box device broken away;

Fig. 3 is a section on line 3—3 of Fig. 2;

Fig. 4 is an enlarged section on line 4—4 of Fig. 3;

Fig. 5 is an enlarged sectional detail on line 5—5 of Fig. 4;

Fig. 6 is a sectional elevation of a device embodying another form of the invention, the plane of the section being indicated by the line 6—6 of Fig. 7;

Fig. 7 is a plan view, partially broken away, of the device of Fig. 6;

Fig. 8 is an enlarged fragmentary section on line 8—8 of Fig. 7; and

Fig. 9 is a fragmentary view as in the plane of Fig. 4 of another form of the invention.

More particularly describing the invention, reference numeral 10 generally indicates the casing of what will be termed a music box. The casing may be made from any of a variety of materials and in a form of the invention shown comprises an upper wall 11, a lower wall including a lower section 12, an upper section 13, and an upright connecting section 14. The casing also includes end walls 15 and 16 and side walls 17 and 18.

Mounted interiorly of the casing on the wall 13 is a music comb 19 which includes a base 20 secured to the wall 13 as by rivets 21. The comb has a plurality of teeth or vibrators 22 which may be mounted in the base in any suitable manner. I prefer to form the teeth 22 from music wire so that they will readily vibrate in any given direction. The vibrators terminate substantially in alignment within relatively close proximity to a drum or rotatable plucking element 25.

The plucking element 25 is shown as comprising a drum including an outer skin of sheet metal 26 from which projections or fingers 27 have been punched to form means for plucking or actuating the vibrators 22 of the comb. The skin 26 is reinforced by a pair of cylindrical inserts 30 and 31 having end flanges 32 and 33, respectively. The drum as a whole is rotatably mounted on a shaft 34, the ends of which extend through openings in the side walls of the casing. One end of the shaft may be provided with a head 35 and the other end secured as by means of a retaining clip 36, suitable spacers 37 being provided between the casing walls and the inserts 30 and 31.

For the purpose of rotating the drum, I provide the flange 33 on insert 31 with gear teeth 39 adapted to mesh with a drive pinion 40 secured to a crankshaft 41 mounted in the side walls of the casing and terminating in a handle 42.

The handle should be operated in a clockwise direction to turn the drum 25 counterclockwise and cause the plucking fingers 27 to selectively engage the vibrator teeth. In a conventional music box it will be apparent that unless the plucking fingers engage only the very tip end portions of the vibrators, the vibrators will be moved a considerable distance before the fingers disengage the vibrators. It is a particular feature of my invention that I provide positive means for disengaging or releasing the vibrator teeth from the plucking fingers after the vibrator teeth have been moved a predetermined, given, or desired amount. I accomplish this by what I have termed a "dijector" or dijector means which will now be described.

I provide means for camming the vibrator teeth out of the path of the plucking fingers as the same move the vibrators. In the form of the invention illustrated the camming or deflecting dijector means comprises a strip of metal or other material 50 which is formed to provide end portions 51 which are secured to the side walls of the casing by rivets 52.

The member 50 is located to lie substantially in a plane at right angles to the plane of the vibrator teeth and relatively transversely thereof near the ends of the vibrators but back a short distance from the ends. The edge of the member 50 facing the vibrator teeth is formed to provide a plurality of angularly disposed cam faces 55 in the path of the respective vibrators as the same are deflected by the rotating plucking fingers on the drum. By referring to Figure 4, it will be apparent that the plucking fingers 27 engage the teeth or vibrators as the drum rotates and deflect the vibrators until they strike the cam faces 55. The cam faces serve to laterally deflect the vibrators until they escape past the plucking fingers. For example, it will be apparent that the plucking finger 27a in Fig. 4 has moved the vibrator 22a into engagement with the cam surface 55a. The next adjacent plucking finger 27b is shown as having moved the vibrator 22b a greater distance and the vibrator has been deflected laterally by the cam face 55b

nearly to the point of release. In the same figure, the plucking finger 27c is shown in a position just after the vibrator 22c has been released therefrom through lateral deflection caused by the cam surface 55c.

It will be apparent that the above means, which I have referred to as a dijector, enables me to control the release or disengagement of the vibrators from the plucking fingers at any desired point and thereby makes possible the construction of a very efficient music box. With the means described, it will be apparent that release or disengagement of the vibrators from the plucking fingers can be accomplished irrespective of the size of the plucking drum or the amount of overlap of the plucking fingers with the vibrators.

In Figs. 6-8 I show a device embodying a rotatable plucking wheel of the disk type and the application of my invention thereto. In these figures, numeral 60 generally indicates the casing of a music box. The casing is provided with a bottom wall 61, and a centrally disposed shaft 62 extends between this wall and a top wall 63. Mounted on the shaft is a rotatable disk 65 which is provided with laterally projecting plucking fingers 67.

The casing is provided with a vertical depending wall 70 and with a second depending wall 71. Mounted on the wall 71 is a music comb 19 which is of the same type as the comb 19 previously described. The comb has vibrators 22 which extend toward the disk 65 with their end portions positioned in the path of the plucking fingers 67 which are arranged in concentric paths on the disk.

I provide a crankshaft 75 which is mounted in the casing 60 parallel to the shaft 62 and at the periphery of the disk 65. This shaft carries a drive wheel or pinion 76 which engages with teeth 77 formed on the periphery of the disk. At the time of assembly guide flanges 78 may be pressed on the pinion 76 to form lateral guides for the disk. I may also provide bifurcated guide tabs 79 on the casing for the disk.

Assuming the handle 80 on the crankshaft 75 is rotated clockwise in the direction of the arrow of Fig. 7 and that the disk rotates counterclockwise in the direction of the arrow thereon, I provide a dijector member 50' immediately behind the teeth 22' of the comb, the dijector being mounted at its ends by means of rivets 82 and 83 on the peripheral wall 84 and wall 70, respectively, of the casing.

The operation of the form of the invention shown in Figs. 6-8 is substantially the same as that previously described, the cam faces of the dijector serving to deflect the vibrator teeth out of engagement with the plucking fingers at the desired point.

While in the devices previously described I have shown the individual plucking fingers as being formed with a flat vibrator-engaging face disposed at right angles to the plane of movement of the finger, I also contemplate that the plucking fingers may be of other shapes, and, for example, in Fig. 9 I show a plucking element 90 adapted to move in the direction of the arrow. This element is provided with plucking fingers 91 each having a forward vibrator-engaging face 92 disposed at an acute angle to the direction of movement of the plucking finger. It will be apparent that with this form of the invention the cam surface 95 of a dijector 96 will more readily deflect the vibrator 97 laterally of the plucking finger to release the same at the

desired point than where the forward face of the finger is at right angles to the direction of travel.

Although the invention has been particularly shown and described, it is contemplated that various changes and modifications may be made without departing from the scope thereof as indicated by the following claims.

I claim:

1. In a music playing device, a plucking element having projecting plucking fingers, a music comb having elongated vibrators extending into the path of said plucking fingers, said element and said comb being relatively movable, and cam means apart from said plucking element in the path of movement of each vibrator when actuated by a plucking finger for deflecting the vibrators out of engagement with said fingers after the vibrators have been moved a given distance by the fingers whereby to positively release said vibrators from said fingers.

2. In a music playing device, a plucking element having projecting plucking fingers, a music comb having elongated vibrators extending into the path of said plucking fingers, said element and said comb being relatively movable, and a dijector member positioned behind the vibrators of said comb adjacent the ends thereof, said member being provided with a cam face for each of said vibrators positioned to be engaged by its respective vibrator upon movement thereof under the influence of a plucking finger, said cam faces each being disposed to deflect its respective vibrator out of the path of the plucking finger.

3. In a music playing device, a rotatable plucking element having projecting plucking fingers, a stationary music comb having elongated vibrators the free ends of which extend into the path of said fingers, and cam means associated with said vibrators for deflecting the vibrators out of engagement with said fingers after the vibrators have been moved a given distance by the fingers whereby to positively release said vibrators from said fingers, said cam means including a surface in the path of movement of each vibrator disposed at an obtuse angle to said path of movement and spaced from the normal position of said vibrator.

4. In a music playing device, a rotatable drum-like plucking element having plucking fingers projecting from the periphery thereof, a stationary music comb having elongated vibrators the free ends of which extend into the path of said fingers, and cam means operatively associated with said vibrators for deflecting the vibrators out of engagement with said fingers after the vibrators have been moved a given distance by the fingers whereby to positively release said vibrators from said fingers, said cam means including a surface in the path of movement of each vibrator disposed at an obtuse angle to said path of movement and spaced from the normal position of said vibrator.

5. In a music playing device, a rotatable disk having concentrically disposed groups of plucking fingers projecting from a side thereof, a stationary music comb having elongated vibrators the free ends of which extend into the path of said fingers, and cam means operatively associated with said vibrators for deflecting the vibrators out of engagement with said fingers after the vibrators have been moved a given distance by the fingers whereby to positively release said vibrators from said fingers, said cam means including a surface in the path of movement of

each vibrator disposed at an obtuse angle to said path of movement and spaced from the normal position of said vibrator.

6. In a music playing device, a rotatable plucking element having projecting plucking fingers, a stationary music comb having elongated vibrators the free ends of which extend into the path of said fingers, and means for disengaging said vibrators from their respective plucking fingers after the vibrators have been moved a given distance by the fingers comprising a dijector member behind the vibrators adjacent their free ends, said dijector member extending transversely of the vibrators and being provided with a cam face for each vibrator, said cam faces being disposed at obtuse angles to the respective paths of movement of the vibrators when actuated by the plucking fingers whereby to deflect the vibrators laterally with respect to the direction of movement imparted to the vibrators by the plucking fingers and prematurely disengage said vibrators respectively from their associated plucking fingers.

7. In a music playing device, a plucking element having projecting plucking fingers, a music comb having elongated vibrators extending into the path of said plucking fingers, said vibrators each being of a cross-sectional shape such as to permit of their vibrating in any plane, said element and said comb being relatively movable, and cam means operatively associated with said vibrators for deflecting the vibrators out of engagement with said fingers after the vibrators have been moved a given distance by the fingers whereby to positively release said vibrators from said fingers, said cam means including a surface in the path of movement of each vibrator disposed at an obtuse angle to said path of movement and spaced from the normal position of said vibrator.

8. In a music playing device, a plucking element having projecting plucking fingers, a music comb having elongated vibrators extending into the path of said plucking fingers, said vibrators being substantially circular in cross section, said element and said comb being relatively movable, and cam means operatively associated with said vibrators for deflecting the vibrators out of engagement with said fingers after the vibrators have been moved a given distance by the fingers whereby to positively release said vibrators from said fingers, said cam means including a surface in the path of movement of each vibrator disposed at an obtuse angle to said path of movement and spaced from the normal position of said vibrator.

9. In a music playing device, a rotatable drum-like plucking element having projecting plucking fingers, a stationary music comb having elongated vibrators the free ends of which extend into the path of said fingers, and means for disengaging said vibrators from their respective plucking fingers after the vibrators have been moved a given distance by the fingers comprising a dijector member behind the vibrators adjacent their free ends, said dijector member extending transversely of the vibrators and being provided with a cam face for each vibrator, said cam faces being disposed at obtuse angles to the respective paths of movement of the vibrators when actuated by the plucking fingers whereby to deflect the vibrators laterally with respect to the direction of movement imparted to the vibrators by the plucking fingers and prematurely disengage said vibrators respectively from their associated plucking fingers.

10. In a music playing device, a rotatable disk plucking element having projecting plucking fingers on one side, a stationary music comb having elongated vibrators the free ends of which extend into the path of said fingers, and means for disengaging said vibrators from their respective plucking fingers after the vibrators have been moved a given distance by the fingers comprising a diector member behind the vibrators adjacent their free ends, said diector member extending transversely of the vibrators and being provided with a cam face for each vibrator, said cam faces being disposed at obtuse angles to the respective paths of movement of the vibrators when actuated by the plucking fingers whereby to deflect the vibrators laterally with respect to the direction of movement imparted to the vi-

brators by the plucking fingers and prematurely disengage said vibrators respectively from their associated plucking fingers.

THEODORE R. DUNCAN.
